SHIPPING CARTON

Colin A. Ross, Troy, N. Y., assignor to Behr-Manning Corporation, Troy, N. Y., a corporation of Massachusetts

Application January 3, 1950, Serial No. 136,470

2 Claims. (Cl. 229—37)

1

The present invention relates to cartons made of heavy paper or cardboard such as the usual corrugated box material used for these purposes.

The carton of the present invention is particularly useful in packaging relatively heavy objects and is adapted to withstand rough treatment during shipment.

For these purposes, I have provided a rigid distortion-free carton of octagonal shape in which the objects to be shipped can be packaged with great rapidity. For example, the carton of the present invention has been successfully used in packaging relatively heavy rolls of sandpaper and the like, and it has superseded the previous method of packaging such rolls wherein they were wrapped in kraft paper and the like, while providing bulk-heads consisting of narrow corrugated rolls with the paper turned in and fastened against the circular flat sides of these bulk-heads. Such previous wrapping practices involved a great many operations and were time consuming, whereas the use of the carton of the present invention more than doubles the speed with which such objects may be packaged.

The particular objects and advantages of the invention will be apparent as the description herein progresses, reference being made to the drawings in which:

Figure 1 is a perspective view of the carton with its end flaps closed and in that condition in which it is substantially ready for shipment;

Figure 2 is a view similar to Figure 1 but with the end flaps of the outer layer raised in order to show the arrangement of the similar flaps of the inner end layer;

Figures 3 and 4 are vertical sectional views through the carton taken along the lines 3—3 and 4—4, respectively, of Figure 1;

Figure 5 is a plan view of an expanded blank from which such a carton may be formed.

The carton is of octagonal configuration having eight side walls or panels 10 of the same size and shape and at each end of the panels, there are hinged flaps which are adapted to be turned in to the top and bottom planes of the carton ends to form reinforced end walls each consisting of two layers.

While all of the flaps are of the same width, there are two pairs of flaps which are relatively long in length and two other pairs of flaps which are relatively short in length in order to obtain a reinforcing action between the flaps as hereinafter described.

As is the usual custom, the blank may be made up in the form of a unitary sheet of the corru-

2

gated material properly formed and cut as shown in Figure 5, and this sheet may then be bent into the octagonal configuration and the union edges 12 and 14 attached to one another in the well-known manner as by a strip of adhesively secured reinforcing tape overlying and securing these edges. Thereafter, the flaps may be bent inwardly to form one end of the carton, the contents then placed in the carton from the open end, after which the flaps of the open end may then be closed and adhesively secured, as herein-after described.

In Figure 2, the inner layer of the carton end is shown being formed by a first pair of opposed flaps 16 and a second pair of opposed flaps 18. The flaps 16 are of such length that their inner edges abut or contact one another in intimate relationship at the center of the carton as indicated at 20. The second pair of opposed flaps 18 are of substantially shorter length, so that they contact the side edges of the flaps 16 in intimate abutting relationship, as indicated at 22, it being apparent that this contact extends centrally along the side edges of the flaps 16 and on both sides of the end edges 20 of the flaps 16.

It will be noted that the flaps 18 extend at substantially right angles to the flaps 16, and that the flaps 16 and 18 are carried on every other panel 10 of the carton. When the flaps 30 are turned inwardly to the plane of the end of the carton as just described, they form an inner layer for the end wall and at the lines of abutting contact 20 and 22 a mutual reinforcing action is provided between the opposite and adjacent panels whereby strength is afforded to withstand impact against the sides and corners of the carton during shipment, and the tendency of the carton to buckle is avoided. Of course, it will be understood that the inner and outer layers are formed at both ends of the carton in the manner described herein. The flaps of the inner end layer may be secured together in any suitable manner and by adhesive tape or they may be simply folded inwardly in contact with one another as shown in Figure 2, after which the flaps forming the outer layer may be glued to those of the inner layer, and to each other, after having been folded inwardly as now to be described.

Alternating with the flaps of the inner layer, there are opposed pairs of the longer flaps 24 and of the shorter flaps 26, which comprise the outer layer of the carton end. The flaps 24 are turned inwardly as shown in Figure 1 until their inner end edges contact each other in tight abut-

ting relationship along the line 30, and thereafter, the shorter flaps 26 are turned inwardly until their inner end edges contact the side edges of the flaps 24 as indicated at 32, it being observed that the lines of contact 32 extend on 5 both sides of the line of contact 30 between the inner ends of the larger flaps 24.

The length of the long and short flaps has a definite relationship to the width of the flaps due to the geometry of the situation. Because 10 the carton is of octagonal configuration having eight side walls of equal size, the angle between adjacent side walls will be 135° . It will also be noted that the width of the side walls is substantially equal to the width of each of the flaps. Therefore, it is now quite obvious that the length of the short flaps 13 and 26 is .707 times the width of the flap as this length will be determined by the sine of a 45° angle. Likewise, the length of the longer flaps 16 and 24 will be equivalent to 15 the length of a shorter flap plus one-half the width of a flap, or thus 1.207 times the width of a flap. Of course, the above figures are based on a carton being geometrically perfect, but due to manufacturing tolerances it might be said that the blank shown in Figure 7 can be manufactured by having the length of the longer flap in the order of 1.2 times the width of a flap or side wall, and the length of the shorter flap in the order of .7 times the width of a flap or side wall. 20

With the end closure thus formed as shown in Figure 1, the carton end comprises two layers, each consisting of opposed pairs of longer and shorter flaps, and the flaps of the outer layer may be adhesively secured to one another as by 25 tape and to the flaps of the inner layer, as desired.

With this construction, it will be observed that the lines of contact 20 and 22 or 30 and 32, in a particular layer, are at right angles to one another, whereas these lines of contact in one layer are at an acute angle to the lines of contact in the opposite layer thus providing an end closure of great strength and which is capable of withstanding impact on the carton from any direction, as against the sides and corners thereof during shipment. The resulting carton is of great rigidity and can be rolled along the floor in the manner of a wheel. Because of the novel arrangement of the flaps, end closures having two layers are provided, and excessive haphazard overlapping and undue thickness throughout the central area at the end of the carton is avoided. If the carton is dropped on any of its edges, there is a reinforcement at each corner of the octagon by reason of the double thickness provided by the overlapping of flaps, and the end and side edge abutment contact as described. The carton has a rigidity and flexibility not present in cartons of conventional design, and while the carton has been found to be particularly useful in packaging rolls of sandpaper or coated abrasive as described, it is obvious that it may be usefully employed in packaging many other types of products. While the carton is of most pronounced usefulness in shipping, it may also

be effectively employed as a container used in dispensing rolled sheet material such as sandpaper without removing the roll from the carton. If this particular use is contemplated, the longer flaps 16 and 24 may be scored, perforated or weakened centrally of the ends of the carton so that a mandrel can be pushed axially through the carton and through the roll contained therein, the mandrel then constituting a shaft around which the carton and the roll may be turned to remove desired lengths or sheets of the sandpaper from the roll. In providing for such use of the carton, spaced lines of perforations or scoring may be provided vertically throughout one of the side panels 10 as shown at 40 in Figure 1, so that a portion of this side wall may be removed to pass the end of the sandpaper sheet on the roll. With this arrangement, a desired length of the sheet material may be pulled outwardly through the slot and then torn off for use.

I claim:

1. An octagonal carton comprising side walls of substantially equal size each having end flaps hinged thereto at both top and bottom, said flaps being turned in forming a two layer reinforced end for the carton, the combined length of an opposed pair of said flaps being equal to the distance between opposed side walls of the carton, said pair of flaps abutting one another at their 25 inner end edges as they exist turned in to the plane of the carton end, the opposed pair of flaps which are disposed ninety degrees from said first pair each having a length equal to one-half the distance between opposed side walls of the carton minus one-half the width of said first pair of flaps, said second pair of flaps abutting the side edges of the flaps of said first pair as they 30 exist turned in to the plane of the carton end, said first and second pair of flaps forming an inner layer of said carton end, correspondingly formed pairs of end edge abutting flaps and side edge abutting flaps carried by the remaining 35 alternating sides of the carton which are turned in forming the outer layer of the carton end, said inner and outer layers being secured together 40 there being such two-layer, flap-formed ends upon both the top and bottom of said carton.

2. A carton as claimed in claim 1 wherein said end edge abutting flaps have a length equal to one-half the distance between opposed side walls 45 of the carton and said inner and outer layers being secured together by a layer of adhesive sandwiched between them.
